CLAIM

The ornamental design for a hand-held vacuum cleaner, as shown and described.

DESCRIPTION

FIG. 1 is a perspective view of a hand-held vacuum cleaner showing our new design, taken from the front right side thereof;

FIG. 2 is a bottom plan view thereof;

FIG. 3 is a left side elevational view thereof;

FIG. 4 is a right side elevational view thereof;

FIG. 5 is a top plan view thereof;

FIG. 6 is a front elevational view thereof; and,

FIG. 7 is a rear elevational view thereof.

The cross hatch shading shown in all views is understood to repeat throughout the indicated area.

FIG. 1

FIG. 2

FIG. 3

FIG. 5

FIG. 6

FIG. 7
